[57] **CLAIM**

The ornamental design for a combined medication and liquid dispensing cup, as shown and described.

DESCRIPTION

FIG. 1 is a perspective view of a combined medication and liquid dispensing cup showing my new design, with the top portion in an open non-use condition;

FIG. 2 is a front elevational view thereof;

FIG. 3 is a top plan view thereof;

FIG. 4 is a bottom plan view thereof;

FIG. 5 is a side elevational view thereof, the opposite side elevational view being identical;

FIG. 6 is a rear elevational view thereof;

FIG. 7 is a perspective view thereof, with the top portion in folded down, use condition; and,

FIG. 8 is a cross-sectional view thereof, taken along line 8—8 of FIG. 7.
